UNITED STATES PATENT OFFICE.

DANIEL ANTON ZURBRIGG, OF MILFORD, DELAWARE, ASSIGNOR TO THE L. D. CAULK COMPANY, OF MILFORD, DELAWARE, A CORPORATION OF DELAWARE.

DENTAL INSTRUMENT.

1,382,401.

Specification of Letters Patent. Patented June 21, 1921.

Application filed May 21, 1918, Serial No. 235,843. Renewed September 17, 1920. Serial No. 410,961.

To all whom it may concern:

Be it known that I, DANIEL ANTON ZURBRIGG, a subject of the King of Great Britain, residing at Milford, in the county of 5 Sussex and State of Delaware, have invented new and useful Improvements in Dental Instruments, of which the following is a specification.

This invention relates to improvements in 10 dental instruments of the type known as "pluggers" or "packers" and which are employed for packing filling materials into tooth cavities. The instruments of the present invention are specially intended for use 15 in connection with the filling of posterior teeth, *i. e.*, molars and bi-cuspids where amalgam or similar material, *i. e.* material which is packed into the cavity while plastic, is employed.

20 The principal objects of the invention are to secure uniformity in the packing of the filling material, to avoid or minimize the possibility of damage to the cavity wall in connection with the packing of the material,

25 to facilitate the filling operation and to provide for the burnishing of the filling in connection with the application thereof.

With the above objects in view the invention is directed more especially to the form 30 of the working points or, more strictly, faces of the instruments and to certain features of combination and arrangement involving the said points or faces, all of which will be set forth in detail as the description proceeds.

35 Instruments in which the invention is incorporated are illustrated in the accompanying drawings, wherein—

Figure 1 is a perspective view of an instrument adapted for mesial cavities.

40 Figs. 2 and 3 are detail side elevations showing the correlative working points at the opposite ends of the instrument.

Fig. 4 is a diagram showing a plan view of a mesial cavity and the larger working 45 point adapted thereto.

Fig. 5 is a diagram showing the outline of a mesial cavity in the mesio-distal dimension and a side elevation of the larger working point adapted thereto.

50 Fig. 6 is a perspective view of an instrument adapted for distal cavities.

Figs. 7 and 8 are detail side elevations showing the correlative working points at the opposite ends of the instrument of Fig. 6.

55 Fig. 9 is a diagram showing a plan view

of a distal cavity and the larger working point adapted thereto.

Fig. 10 is a diagram showing the outline of a distal cavity in the mesio-distal dimension and a side elevation of the larger working point adapted thereto.

Figs. 11 and 12 are diagrams of the correlative packing faces, in two different sizes thereof, of the instruments shown in Figs. 1 to 6 respectively.

Similar characters of reference designate corresponding parts throughout the several views.

Simple mesio-occlusal (Figs. 4 and 5) or disto-occlusal (Figs. 9 and 10) cavities as 70 prepared for filling are of a general or roughly triangular outline and have buccolingual and mesio-distal dimensions in the approximate ratio 4:3. For packing the filling material in such cavities I have found 75 that the best results are obtained by the employment of packing faces which have the outline of an isosceles trapezoid with their surface dimensions in the ratio 4:3. I have also found that for condensing the filling material into the undercuts and the angles of the matrix with the cavity walls, the best results are obtained by employing 80 a correlative packing face of the same outline, arrangement and dimensional proportions but of considerably reduced area. The form of the packing faces is the same for either mesial or distal cavities but for mesial cavities the longer parallel side of the trapezoid faces anteriorly while for distal cavities 85 it faces posteriorly.

Thus, to obtain the best results, two correlative packing faces should be employed for the filling of a single cavity, the smaller face being adapted to condense the material 95 into the undercuts and the angles of the matrix with the cavity walls and the larger face being adapted for the final condensation of the material. It is preferred to provide the two correlative packing faces on a single instrument adapted to mesial or distal cavities, as the case may be, Fig. 1 showing an instrument adapted to mesial cavities and Fig. 6 showing an instrument adapted to distal cavities. Referring to Fig. 1 the larger 100 packing face for final condensation is shown at 1 and the smaller correlative packing face is shown at 2, these faces being arranged at opposite ends of the instrument. Referring to Fig. 6, the larger packing face for 105 110

final condensation is shown at 1^a and the smaller correlative packing face at the opposite end of the instrument is shown at 2^a. For use in both mesial and distal cavities 5 the packing faces are smooth and plane or flat. Such faces effect a stronger and more homogeneous condensation of the amalgam and also produce a burnishing effect. The packing faces are preferably somewhat 10 rounded at the corners whereby to avoid sharp angles and this feature, in conjunction with the smoothness of such faces, minimizes the liability of danger to the cavity walls or margins.

15 The packing faces are formed at the ends of short sturdy shanks 3, whose cross sectional outline conforms to the outline of said faces and which are provided at the ends of a suitably elongated handle or body portion 20 4. The shanks 3 are preferably arranged contra-angle in order that said faces may be arranged close to the major axis of the handle or body portion 4, thereby to enable the most efficient application of the force 25 applied.

For mesial cavities the planes of the packing faces should form an angle of approximately 40° or slightly less with a line X touching the most advanced edge of said plane and parallel to the axis of the handle 4, and the shanks 3 by which said packing faces are carried are preferably arranged with their axes at angles of approximately 30 90° to said faces. The angular relation of 35 the mesial packing faces to the line X in connection with the inclination at which the instrument is held, insures that the gingival portion of the filling shall be automatically condensed first and with the most efficient 40 effect. The same angular relation of the packing faces to the line X if applied to the instrument adapted for a distal cavity would have the least effect in the condensation of 45 the amalgam upon the deep gingival margins. Accordingly the planes of the packing faces 1^a and 2^a for the distal cavities 50 form a reduced angle, approximately an angle of 25°, with the line X, such reduced angle insuring adequate condensation and adaptation of the amalgam to the vital gingival margin.

In both cases, therefore, the packing faces are arranged in angular planes best calculated to adapt them to the cavities, mesial or distal, for which they may be intended.

It has been found that for the larger restorations the best condensation effects are achieved by packing faces 1 or 1^a, as the case may be, of 4mm. x 3mm. dimensions.

60 Where the packing faces 1 or 1^a are of such dimensions the correlative packing faces 2 or 2^a should be of one-fourth the area of the faces 1 or 1^a, i. e. of 2mm. x 1.5mm. dimensions. For smaller cavities the instruments 65 while possessing the features of structure

and arrangement above described, will have their working faces 1 or 1^a somewhat smaller and their correlative working faces 2 or 2^a a considerably smaller fraction of the area of the working faces 1 or 1^a, the preferred 70 dimensions being 3mm. x 2.25mm. for the faces 1 or 1^a and 1mm. x .75mm. for the faces 2 or 2^a.

It will thus be seen that the relation of 75 the areas of the correlative packing faces is not the same in both cases and, therefore, may not be expressed generically by a fraction. Accordingly the term "correlative" as applied to the packing faces is used in this description and in the appended claims to 80 describe packing faces whose areas are in such relation that the larger face will be adapted to the final packing of a cavity and the smaller face will be adapted to condensing the filling material into the undercuts 85 and angles between the matrix and walls of the same cavity. The specification otherwise clearly indicates the details and relation of these correlative packing faces in all necessary instances of their use.

90 Two instruments will, therefore, serve for all mesial cavities. Two others, duplicates, except for the modification of the angle of the planes of the packing faces and of the arrangement of the longer sides of the said 95 faces posteriorly will serve for all distal cavities, and will complete the series. The four instruments of the series may be appropriately distinguished from one another by suitable marking. Thus, as shown diagrammatically in Fig. 11, the instrument with the larger faces for mesial cavities may be marked with the indicia M⁴—M² and the instrument with the smaller faces for mesial cavities may be marked M³—M¹, while the 100 two instruments for distal cavities may in like manner, as shown diagrammatically in Fig. 12, be marked D⁴—D² and D³—D¹, respectively, the letter indicating mesial or distal and the numbers giving the largest 105 face dimensions of the respective working terminals.

110 A cavity large enough to require the face M⁴ or D⁴ for final condensation would require the correlative face M² or D² respectively, for the packing of its undercuts and matrix angles, the faces M³ or D³ being too large and the faces M¹ or D¹ too small for this first service. On the other hand a smaller cavity requiring the face M³ or D³ 115 for final packing would require the correlative face, M¹ or D¹ respectively, for the initial packing of its undercuts and matrix angles.

Having fully described my invention I 120 claim —

1. An instrument for packing filling material into occlusal posterior-teeth-cavities, having correlative larger and smaller trapezoidal packing faces, each of whose greater 125

dimensions is transverse and whose dimensional ratio is 4:3.

2. An instrument for packing filling material into occlusal posterior-teeth-cavities, 5 having a smooth, plane trapezoidal packing face whose dimensional ratio is 4:3 and whose corners are rounded.

3. An instrument for packing filling material into occlusal posterior-teeth-cavities, 10 having a smooth plane trapezoidal packing face whose greater dimension is transverse and whose dimensional ratio is 4:3.

4. An instrument for packing filling material into occlusal posterior-teeth-cavities, 15 having correlative larger and smaller smooth, plane trapezoidal packing faces and an elongated handle or body portion provided at its ends with shanks upon which said packing faces are formed.

20 5. An instrument for packing filling material into occlusal posterior-teeth-cavities, having correlative larger and smaller smooth, plane trapezoidal packing faces and an elongated handle or body portion provided at its ends with shanks upon which 25 said packing faces are formed, said packing faces having their planes disposed at the same angles to lines touching their most advanced edges and parallel to the axis of

said handle or body portion and said angles 30 being correlated to said faces to insure that they will first act with full effect upon the portion of the filling adjacent the gingival margins of the cavity.

6. An instrument for packing filling material into occlusal posterior-teeth-cavities, 35 provided with correlative larger and smaller smooth, plane packing faces, each having similarly disposed longer and shorter transverse edges, and an elongated handle or 40 body portion provided at its ends with shanks upon which said packing faces are formed, said packing faces having their planes disposed at the same angles to lines touching their most advanced edges and 45 parallel to the axis of said handle or body portion and also having their planes whereby they will first act with full effect upon the portion of the filling adjacent the gingival margins of the cavity. 50

In testimony whereof I have hereunto set my hand in the presence of two subscribing witnesses.
